Des. 1087

Henry C. Foot, of Wallingford, Conn.
Letters Patent No. 1087, Dated March 8, 1859.

The schedule referred to in their Letters Patent and making part of the same.

To all whom it may concern:

Be it known that I, Henry C. Foot, of Wallingford, in the County of New Haven, and State of Connecticut, have invented or produced a new and original design for a Tea-Bell, and I do hereby declare the following to be a full, clear and exact description of the same reference being had to the accompanying drawing making a part of this Specification and which represents an elevated perspective of the bell in question.

A. represents the base of the bell, which may be of any suitable size to give a firm support to the figure B, that surmounts it.

This base may be ornamented with scroll work or plain concavo-convex moulding. A stem C. rises from the centre of this base, to which the hollow body of the figure B. is suspended so as to leave an open space between the bottom of the drapery of the body, and the top of the base, through which, the spring ^{over} D. that operates a striker, may pass - said body forming a bell, on top of the stem C. is placed the head and bust of the figure which as well as the body, is covered with drapery or dress of modern style. The whole forming a neat and original design for a Tea-bell.

Having thus fully described my invention or production what I claim is a design for a Tea-Bell composed of an ornamented base mounted by a female figure, as herein represented.

Witnesses.
